(57) CLAIM

The ornamental design for a notebook with fur, as shown and described.

DESCRIPTION

FIG. 1 is perspective view of the notebook with fur, showing my new design;

FIG. 2 is a front view of the notebook with fur of FIG. 1; FIG. 3 is a rear view of the notebook with fur of FIG. 1; FIG. 4 is left side view of the notebook with fur of FIG. 1; FIG. 5 is a right side view of the notebook with fur of FIG. 1;

FIG. 6 is a top down view of the notebook with fur of FIG. 1; and,

FIG. 7 is a bottom up view of the notebook with fur of FIG. 1.

The broken lines that are immediately adjacent to the claim represent the bounds of the claim, while all other broken lines are directed to environment; the broken lines form no part of the claimed design.
